UNITED STATES PATENT OFFICE

168,578

ELECTRIC MEGAPHONE

Edwin B. Levinson, Van Nuys, Calif.

Application January 15, 1952, Serial No. 18,072

Term of patent 14 years

(Cl. D26—14)

To all whom it may concern:

Be it known that I, Edwin B. Levinson, a citizen of the United States and a resident of the city of Van Nuys, in the county of Los Angeles, and State of California, have invented a new, original, and ornamental Design for an Electric Megaphone, of which the following is a specification, reference being had to the accompanying drawing, forming part thereof, in which:

Fig. 1 is a perspective view of an electric megaphone showing my new design;

Fig. 2 is a side view; and

Fig. 3 is a top view of my megaphone. The dotted line showing is for illustrating a general form of supporting device when the megaphone is not in use.

I claim:

The ornamental design for an electric megaphone, as shown and described.

EDWIN B. LEVINSON.
